UNITED STATES PATENT OFFICE.

CHARLES H. PATTEN, OF PROVIDENCE, RHODE ISLAND, ASSIGNOR TO BEX MANUFACTURING CO., OF PROVIDENCE, RHODE ISLAND, A CORPORATION OF RHODE ISLAND.

WRITING INSTRUMENT.

Application filed April 16, 1925. Serial No. 23,704.

To all whom it may concern:

Be it known that I, CHARLES H. PATTEN, a citizen of the United States, residing at Providence, in the county of Providence and State of Rhode Island, have invented 5 certain new and useful Improvements in Writing Instruments, of which the following is a specification.

This invention relates to an improvement 10 in the construction of mechanically-actuated pencils, more particularly to the resilient holding clip or arm attached thereto, and the object of this invention is to provide simple and effective means for connecting 15 one end of this resilient holding clip to one of the members of the pencil to provide a strong and durable construction and reduce the cost of attaching this arm to the pencil.

With these and other objects in view, the 20 invention consists of certain novel features of construction, as will be more fully described and particularly pointed out in the appended claims.

In the accompanying drawings:—

25 Figure 1 is a side elevation partly in section illustrating one means for securing one end of the binding clip to the pencil.

Figure 2 is a detail partly in section showing an enlarged view of a nut threaded 30 onto the collar of the plug for binding one end of the resilient holding arm or clip to the plug.

Figure 3 shows another simple way of 35 rolling the collar of the plug to bind the clip arm thereto.

Figure 4 shows a cap which may be formed of plated stock, embracing the collar of the plug and the clip arm secured thereto.

Figure 5 is a perspective view of the clip 40 showing the offset end with an opening therein.

It is found in practice, of advantage to produce simple and effective means for attaching the laterally turned upper end of 45 the resilient clip arm of a pencil to the threaded plug therein in such a way as to make it strong and durable and yet to reduce the cost of such attaching to the very minimum; and the following is a detailed 50 description of the present embodiment of my invention showing one means by which these advantageous results may be accomplished:—

With reference to the drawings 10 designates the body of a pencil which is pref-

erably made of rubber tubing of any desired shape and color, the upper end 11 of which is preferably threaded internally as at 12 to receive the threaded plug 13. This plug is preferably formed of brass threaded 60 at 14 to be screwed into the threaded end of the tube and this plug is provided with an enlargement or shoulder 15 which rests against the end of the rubber tubing and above this shoulder is preferably formed a 65 collar portion 16 which in some instances, may be threaded on its outer surface as at 17 and provided with a nut 18.

The resilient clip 19 which is for the purpose of retaining the pencil in the pocket 70 of the user is arranged to extend down along the barrel of the pencil and is provided with a laterally offset portion 20 which is pierced as at 21 to embrace or fit 75 over the collar portion 16 of the plug. The nut 18 on this threaded collar being then screwed down onto this offset portion of the clip to secure and bind it against the enlargement or shoulder 15.

In other instances instead of threading a 80 nut 18 onto the collar portion of the plug, I turn this collar portion outwardly as at 22, see Figure 3, and so bind this laterally extending portion 20 of the clip 11, to the shoulder 15 of the plug.

In still other cases I may form a cup member 23, as illustrated in Figure 4, preferably of plated metal and pierce the center of the cup as at 24 and to the outer face of this cup I secure, by solder or other 90 means, the laterally turned end 20 of the clip and then connect this collar to the shoulder 15 of the plug either by turning the edge 25 of this cup inwardly over the lower edge of the shoulder or by soldering 95 or otherwise.

My improved means of securing the clip to the plug is very simple and practical and materially reduces the cost of construction to the minimum.

The foregoing description is directed 100 solely towards the construction illustrated, but I desire it to be understood that I reserve the privilege of resorting to all the mechanical changes to which the device is 105 susceptible, the invention being defined and limited only by the terms of the appended claims.

I claim:—

1. A writing instrument having a barrel 110

portion, a threaded bearing guide plug screwed into one end of said barrel, said plug having a shoulder and a collar portion extending above said shoulder, a spring 6 clip having a resilient arm lying along said barrel portion and having a laterally extending end with an opening therein embracing said collar, and means being provided for securing said clip end to said shoulder.

2. A writing instrument having a barrel portion, a threaded bearing guide plug screwed into one end of said barrel, said plug having a shoulder and a collar portion 16 extending above said shoulder, a spring clip having a resilient arm lying along said barrel portion and having a laterally extending end with an opening therein embracing said collar, and means on the collar portion for 20 binding said clip end portion to said shoulder.

3. A writing instrument having a barrel portion, a threaded bearing guide plug screwed into one end of said barrel, said 25 plug having a shoulder and a threaded col-

lar portion extending above said shoulder, a spring clip having a resilient arm lying along said barrel portion and having a laterally turned end with an opening therein embracing said threaded collar, and a nut on 30 said collar for binding said clip end to said shoulder.

4. A writing instrument having a barrel portion, a threaded bearing guide plug screwed into one end of said barrel, a spring 35 clip having a resilient arm lying along said barrel portion and having a laterally-extending end immovably secured to the plug to prevent a relative rotation of said clip and plug.

5. A writing instrument having a barrel portion, a threaded bearing guide plug screwed into one end of said barrel, a spring clip having a resilient arm lying along said barrel portion and having a laterally-extending end with an opening therein receiving a portion of said plug, and means 45 for securing said clip end to said plug.

In testimony whereof I affix my signature.
CHARLES H. PATTEN.

- portion, a threaded bearing guide plug screwed into one end of said barrel, said plug having a shoulder and a collar portion extending above said shoulder, a spring 5 clip having a resilient arm lying along said barrel portion and having a laterally extending end with an opening therein embracing said collar, and means being provided for securing said clip end to said shoulder.
- 10 2. A writing instrument having a barrel portion, a threaded bearing guide plug screwed into one end of said barrel, said plug having a shoulder and a collar portion 15 extending above said shoulder, a spring clip having a resilient arm lying along said barrel portion and having a laterally extending end with an opening therein embracing said collar, and means on the collar portion for 20 binding said clip end portion to said shoulder.
- 15 3. A writing instrument having a barrel portion, a threaded bearing guide plug screwed into one end of said barrel, said 25 plug having a shoulder and a threaded col-
- lar portion extending above said shoulder, a spring clip having a resilient arm lying along said barrel portion and having a laterally turned end with an opening therein embracing said threaded collar, and a nut on 30 said collar for binding said clip end to said shoulder.
4. A writing instrument having a barrel portion, a threaded bearing guide plug screwed into one end of said barrel, a spring 35 clip having a resilient arm lying along said barrel portion and having a laterally-extending end immovably secured to the plug to prevent a relative rotation of said clip and plug.
5. A writing instrument having a barrel portion, a threaded bearing guide plug screwed into one end of said barrel, a spring 40 clip having a resilient arm lying along said barrel portion and having a laterally-extending end with an opening therein receiving a portion of said plug, and means for securing said clip end to said plug.

In testimony whereof I affix my signature.
CHARLES H. PATTEN.

DISCLAIMER.

1,548,548.—*Charles H. Patten*, Providence, R. I. WRITING INSTRUMENT. Patent dated August 4, 1925. Disclaimer filed December 8, 1925, by the patentee, Charles H. Patten, assignee, *Rex Manufacturing Company*, consenting.

Hereby enters this disclaimer to the claims in said specification which are in the following words, to wit:

“1. A writing instrument having a barrel portion, a threaded bearing guide plug screwed into one end of said barrel, said plug having a shoulder and a collar portion extending above said shoulder, a spring clip having a resilient arm lying along said barrel portion and having a laterally extending end with an opening therein embracing said collar, and means being provided for securing said clip end to said shoulder.

“4. A writing instrument having a barrel portion, a threaded bearing guide plug screwed into one end of said barrel, a spring clip having a resilient arm lying along said barrel portion and having a laterally extending end immovably secured to the plug to prevent a relative rotation of said clip and plug.

“5. A writing instrument having a barrel portion, a threaded bearing guide plug screwed into one end of said barrel, a spring clip having a resilient arm lying along said barrel portion and having a laterally extending end with an opening therein receiving a portion of said plug, and means for securing said clip end to said plug.”
